UNITED STATES PATENT OFFICE.

EDWARD A. T. HOLDEN, OF DULUTH, MINNESOTA.

GRAIN-SCRAPER.

1,353,341.

Specification of Letters Patent. Patented Sept. 21, 1920.

Application filed December 30, 1919. Serial No. 348,279.

To all whom it may concern:

Be it known that I, EDWARD A. T. HOLDEN, a citizen of the United States, residing at Duluth, in the county of St. Louis and State of Minnesota, have invented certain new and useful Improvements in Grain-Scrapers, of which the following is a specification, reference being had therein to the accompanying drawing.

10 This invention relates to scrapers and has special reference to a grain scraper such as are commonly employed about grain elevators in unloading grain from cars, emptying bins in the elevators and the like.

15 Such scrapers are usually made of wood, are drawn when scraping by a power actuated bridle, and controlled manually by suitable handles near the upper edge thereof.

It is found in practice that these scrapers 20 are subjected to considerable abuse by bumping against fixed parts of the car in which they are used and against the sides of the openings in either a car or bin as the case may be.

25 This causes frequent breakage, necessitating quite extensive repairs and frequently entire renewal.

The parts of the scraper most frequently broken are the comparatively narrow side 30 pieces, and when these are badly damaged it often requires taking the entire scraper apart, and as before stated results in quite an extensive and expensive operation. To avoid this and increase the life as well as 35 to some extent the capacity of the scraper is the principal object of this invention.

Other objects and advantages of the invention will appear in the further description thereof.

40 The accompanying drawing forming part of this application is a perspective view of one of the improved scrapers.

Referring to the drawing by reference numerals, 1 and 2 represent the boards 45 forming the flat bottom of the scraper. 3 is the upper edge board which is inclined outwardly from the interior of the scraper and to which the controlling handles 4 are attached. 5 and 6 are the bottom nose 50 boards which are inclined upwardly from the board 1, and the board 5 carries suitable hooks 7 to which the pulling bridle, not shown, is attached. All these are as commonly found on such scrapers and none

of which form independent parts of my 55 present invention.

But the side boards of the scraper embody the novel features. 8 represents the upper metal-holding portion of the sides and 9 the wooden nose pieces or lower portions thereof.

The holders 8 are of straight flat pieces of sheet metal having inwardly projecting edges turned at right angles thereto forming a continuous flange 10 entirely about the 65 edges thereof except on the end toward the nose of the scraper, and into which open end the upper end of the wooden nose pieces 9 are fitted and secured by suitable through bolts 11. The upper or inner ends of the 70 nose pieces are rounded off as at 12 to prevent obstruction to the ready discharge of grain and the bottom and nose boards 1, 5 and 6 are fastened to the under edges of the board 9 by screw nails as is customary. 75

The boards 2 and 3 are fastened to the inside of the flanges 10 of the metal holders by suitable bolts, some of which are indicated at 13, and the uppermost corners of the holders are inclined downwardly as at 80 14 for better appearance and improvement in shape generally.

From the foregoing it is evident that if any one or more of the nose boards become broken or badly worn, they may be readily 85 replaced without disassembling the whole scraper, and that the upper portion of the sides being of metal will outwear a number of sets of wooden nose pieces. Again, if the holder-sections 8 become bent or misshapen 90 they can readily be brought back to normal shape and continued in service.

Having thus described my invention, what I claim is:

1. The combination with a scraper of the 95 character described made principally of wood, of holding side pieces made of flanged metal and wooden side nose pieces fitted into the lower ends of the metal holding pieces and to which latter the bottom nose boards 100 are attached.

2. A scraper of the character described composed principally of wood and having main side pieces composed of sheet metal, flanged inwardly and firmly binding the 105 major portion of the parts of the scraper together.

3. The combination with a scraper of the

class described comprising a substantially rectangularly shaped main body portion and an upwardly inclined nose portion to the inside of which is attached the draft lines, 5 the sides of the body portion being made of inwardly flanged sheet metal pieces, to which the bottom and rear end are permanently fastened and side nose pieces removably fastened into the open ends of the 10 flanged pieces and supporting the inclined

bottom nose portion outside of the draft line connections, substantially as and for the purpose described.

In testimony whereof I hereunto affix my signature in the presence of two witnesses. 15

EDWARD A. T. HOLDEN.
